US0D1001459S

(12) **United States Design Patent** (10) **Patent No.:** **US D1,001,459 S**
(45) **Date of Patent:** **** Oct. 17, 2023**

(54) **SHOE**

(71) Applicant: **LaCrosse Footwear, Inc.**, Portland, OR (US)

(72) Inventor: **Gabriel Freedom Phillips**, Portland, OR (US)

(73) Assignee: **LaCrosse Footwear, Inc.**, Portland, OR (US)

(**) Term: **15 Years**

(21) Appl. No.: **29/812,890**

(22) Filed: **Oct. 25, 2021**

Related U.S. Application Data

(63) Continuation of application No. 29/732,924, filed on Apr. 28, 2020, now Pat. No. Des. 943,909, which is a continuation of application No. 29/643,665, filed on Apr. 10, 2018, now Pat. No. Des. 883,639.

(74) *Attorney, Agent, or Firm* — Perkins Coie LLP

(57) **CLAIM**

The ornamental design for a shoe, as shown and described.

DESCRIPTION

FIG. 1 is a perspective view of a shoe showing my new design.

FIG. 2 is a right-side view thereof.

FIG. 3 is a left-side view thereof.

FIG. 4 is a front view thereof.

FIG. 5 is a rear view thereof.

FIG. 6 is a top view thereof; and,

FIG. 7 is a bottom view thereof.

The broken lines in the drawings illustrate portions of the shoe that form no part of the claimed design.

1 Claim, 7 Drawing Sheets
